ELECTROHYDRAULIC MOTOR

Frank H. Smith, Summit, N. J., assignor to
Elevator Supplies Company, Incorporated,
Hoboken, N. J., a corporation of New Jersey

Original application December 31, 1930, Serial No.
505,934. Divided and this application November
19, 1931, Serial No. 576,101

9 Claims. (Cl. 60—52)

This invention relates to motors of the electro-hydraulic type in which the energy of a high-speed electric motor is converted so as to apply power at a relatively slow speed in a simple and flexible manner, for example to supply energy for operating parts on moving objects such as elevator cars, and provides improvements therein.

This application is a division of my application Serial No. 505,934, filed December 31, 1930.

The invention provides electro-hydraulic means to operate elevator doors or gates, for example in such manner that there is obtained a strong and adequate force for operating the elevator doors, almost instant action at the maximum force, almost instantaneous reversing movements of the doors at any stage of movement thereof, resilient and flexible movement of the doors and connected parts, different speeds of opening and closing, limitation of the driving force acting on the doors when the doors strike a person or obstruction, automatic checking and stopping of the doors at the end parts of their movements, holding or locking of the doors in their open and closed positions, and relief of the doors from the driving force of the electro-hydraulic device in their open and closed positions, even though the electric motor continues to run.

The invention further provides an electro-hydraulic motor comprising an impeller driven in one direction by the electric motor, together with means for obtaining reversing movements of the hydraulic element.

The invention further provides an electro-hydraulic motor combined with means for checking or cushioning its action at the end parts of its action, whereby to effect a cushioning or gradual stopping of the parts operated by the motor and prevent shocks and noise of the parts in coming to a stop at the end position or positions. It further provides means for effecting adjustment of the cushioning or checking action, whereby such checking action may be varied as desired.

The invention further provides a compact and simple form of reversing electro-hydraulic motor, in which the construction is such that the motor is not liable to get out of order, which is capable of being fitted into restricted spaces, in which the valve mechanism is closely associated with the impeller and its housing, and in which in fact the impeller housing may have the additional function of a valve. It further provides a reversing electro-hydraulic motor which acts almost instantly with its full force,

which does not build up an undue or dangerous force when the part or parts operated thereby meet an obstruction, and in which the electric motor and the impeller driven thereby may continue to run without binding or strain when the part operated by the motor meets an obstruction, or when the electric motor continues to run after the valve has been moved to a cut-off position.

Several embodiments of the invention are illustrated in the accompanying drawings, wherein:

Figure 1 is a vertical sectional view of one embodiment of the electro-hydraulic motor, shown as operatively connected to a sliding door such as used on subway cars, the section being on line I—I, Fig. 2.

Fig. 2 is a top plan view of the parts shown in Fig. 1.

Fig. 3 is a horizontal sectional view on the line III—III, Fig. 1.

Fig. 4 is an enlarged horizontal sectional view of the pump shown in the lower part of Fig. 1, and showing the valve in position cutting the pump off from the hydraulic motor.

Fig. 5 is a view similar to Fig. 4 showing the valve in position for driving the piston of the hydraulic motor, shown in Fig. 1, to the left.

Fig. 6 is a view in elevation of parts of the mechanism for operating the valve which controls the flow of liquid from the pump to the hydraulic cylinders.

Figs. 7 and 8 are respectively a horizontal sectional view and a vertical sectional view of another embodiment of the pump and valve shown in Figs. 1—6 inclusive; the housing of the impeller combining the function of a valve in Figs. 1—6 and in Figs. 7 and 8 the valve and impeller housing are separate.

Figs. 9 and 10 are views similar to Figs. 7 and 8 and illustrating a third embodiment of pump in which the pressure of the liquid is stepped up by the driving action of a series of impellers, the section in Fig. 10 being on line X—X, Fig. 9.

One embodiment of the electro-hydraulic motor is illustrated in Figs. 1 to 6, inclusive. The motor is shown as applied to the simple operation of opening and closing a sliding door D. Numeral 10 designates the electro-hydraulic motor as a whole. Numeral 12 designates an electric-motor of suitable construction being preferably a constant speed motor. Numeral 14 designates a pump driven by the electric motor 12, and numeral 16 designates a double-acting hydraulic cylinder, said cylinder comprising the portions 19 and 20 and the double-acting piston 22 comprising

the portions 23 and 24, hereinafter more fully explained. Ports 27 and 28 lead from the pump to each side of the piston 22, to serve for conveying fluid under pressure to one side or other of the double-acting piston 22, and also conveniently to serve as passages through which the fluid on one side of the piston may be vented when fluid is being supplied to the opposite side.

In order to provide compactness of construction and to obtain other advantages, the pump 14 is conveniently located about midway of the cylinder 16, and conveniently slightly below its axis, and the electric motor 12 is conveniently located over the pump 14.

15 The pump 14 comprises a wheel or impeller 30 within a suitable housing 32. The impeller or wheel 30 is preferably keyed upon a shaft 34 which is driven directly by the motor 12. A reservoir for fluid is conveniently provided by a space 36 between the two cylinder portions 19 and 20 of the double-acting cylinder 16, the portions 19 and 20 being spaced to provide this reservoir. The reservoir 36 is conveniently of about the same width as the diameter of the cylinder. The 25 wheel 30 as here shown is of the balanced double impeller type, and passages 38, 39, through the impeller housing 32 lead to the intake of the upper and lower portions of the wheel, Fig. 1, the passages 38 being directly in communication with the reservoir 36, and the passages 39 being in communication therewith through the channels 41 around the impeller housing. See Figs. 4 and 5. The pump 14 has a peripheral chamber 40 into which the impeller 30 forces liquid when 35 driven.

Power is preferably taken from the piston 22 at a point intermediate the double-acting cylinder. The power is conveniently taken from a shaft 44 running across the upper part of the reservoir, 40 at a level which is conveniently above the level of the oil in the device, whereby to eliminate the necessity for packing around moving parts passing through the cylinder, the cylinder, reservoir and pump housing being conveniently formed in one piece, as shown. The ends of the cylinder 16 are covered by caps 45, 46. As above stated, the shaft 44 passes through the housing above the oil level, and no other moving part passes through the housing below this point. Inspection 45 holes 12^a with removable cover plates may be provided in the upper part of the casing for observation of the operation of the parts and the oil level.

As before stated, the double-acting piston 22 is 55 conveniently separated into two parts 23, 24, which are connected through the reservoir 36 by means of a thrust-rod 50. Means are provided for connecting the piston 22 in driving relation with rock-shaft 44. To this end, thrust-rod 50 60 is conveniently provided with a rack 52 adapted to mesh with a gear segment 54 fixed upon the aforesaid shaft 44. For the purpose of symmetry, the thrust-rod 50 is conveniently formed as a divided or rectangular frame, and the rack 52 is conveniently formed on the two long sides thereof, and the segmental gear 54 duplicated, as showing in 54, to engage with the rack portion 52' on the thrust-rod or frame 50. The frame construction of the thrust-rod further permits of the impeller shaft 34 passing downwardly to the impeller through the axis of the double-acting cylinder 16. The shaft 44 on which the segmental gears 54, 54' are mounted, and which transmits the power of the hydraulic piston 22, is conveniently cored in its middle, as indicated at 58, to

permit of the impeller shaft 34 passing through the same, and of the said shaft 44 rocking without hitting the shaft 34.

As heretofore stated, the electric motor 12 is preferably a motor of the type which is energized to run in one direction, and consequently the impeller 30 of the pump also runs in one direction. Means are provided for having the one-way driven impeller act to effect movement of the piston 22 in reverse directions, whereby 10 to effect rocking movement of the shaft 44, and consequently a back and forth movement to the part connected to the motor, as for example to effect the opening and closing movements of a door. This means conveniently comprises a 15 valve for connecting the pressure chamber 40 of the pump 14 to one or other of the cylinder portions 19, 20. In the construction illustrated in Figs. 1, 4 and 5, the impeller housing 32 is preferably given the function of a valve. To this end 20 the impeller housing 32 is conveniently rotatably fitted in the pump housing 14, so as to be capable of being oscillated therein as hereinafter described. The impeller housing is provided at the two sides thereof with outlet openings 60, 61, 25 in communication with chamber 40 and placed so that one registers with one or other of the passages 27, 28, when the other is out of register with said passages, or vice versa. For example, as shown in Fig. 5, the outlet passage 61 registers with the passage 28 leading to the cylinder portion 20, while at the same time the outlet passage 60 is cut off from the passage 27 leading to the opposite cylinder portion 19. Furthermore, the angular relation of the outlets 60, 61 30 35 is preferably such that the impeller housing containing these passages 60, 61 may be turned to a position wherein the outlet ports 60, 61 are cut off from both passages 27, 28 leading to the cylinder ends. This position is shown in Fig. 4, 40 wherein it will be seen that the outlet passages 60, 61 are out of register with both passages 27, 28.

Means 65 are provided for moving the valve controlling the flow of liquid to the cylinder ends 45 19 and 20. The valve (in this case the impeller housing 32) is conveniently provided with a gear or segment 67 fixed to a neck 68 thereof concentric with the axis of the shaft 34. This gear 67 meshes with a gear segment 69 carried by a 50 shaft 70, extending upwardly through the reservoir and upwardly through the cylinder housing or casing, preferably at a point above the liquid level therein, as shown. A lever or arm 72 is conveniently fixed to the upper exterior end of 55 the shaft 70, as shown, and the shaft 70, and consequently the valve (impeller housing 32) moved back and forth by moving the arm 72 back and forth. The arm 72 is conveniently moved by an electric engine 75 (or other suitable means) 60 through suitable linkage, as shown at 77. Engine 75 is here shown as a pair of solenoids 75^a, 75^b provided with movable cores 80, 81. The cores 80, 81 are connected to a rocking beam 83, which is in turn connected to the link 77. When one or the other of the solenoids is energized to attract its armature 80, 81, the valve 32 (impeller housing) is shifted from a position to admit fluid to one end 19, 20 or the other of the hydraulic cylinder, as hereinafter more fully explained in 65 70 the description of operation.

Means are preferably provided for automatically checking the piston 22 at the ends of its stroke, and thereby cushioning the end portions of the movement of the part moved thereby, as 75

for example the opening and closing movements of the door shown. The cushioning is conveniently effected through the valve 32, and to this end connections may be provided between 5 the shaft 44 and the said valve 32. These operating means or connections conveniently comprise a pair of cams 90, 91 fixed upon the rock shaft 44, and means for transmitting the motion from each of these cams to the gear 67. 10 These means conveniently comprise a pair of rock shafts 93, 94, having arms 95, 96 thereon so positioned as to be struck and moved at proper times by the said cams 90, 91. The rock shafts 93, 94 are preferably arranged to pass through 15 the cylinder casing above the liquid level therein, and are provided at their inner ends with worm gears 97, 98 which mesh with worms 100, 101 fixed upon vertical shafts 103 and 70 having gear segments 104 and 69 at their lower ends in 20 mesh with the gear 67 fixed to the valve 32 (the shaft 70 and gear segment 69 also serving for conveying motion imparted to the rock arm 72 to the valve 32 through gear 67, as heretofore explained). When rock-shaft 93, gears 97, 100, 25 shaft 103 and segment 104 are actuated, the segment 69, shaft 70, gears 98, 101 and rock-shaft 94 move reversely.

The cams 90 and 91 are preferably fixed upon the end of the shaft 44 by means of a clamping 30 nut 107. Loosening of this nut permits of shifting of the angular position of one or both of the said cams 90, 91 and thereby permits of adjustment or timing of the checking or cushioning action through the operation of the parts 35 just described. The cams 90, 91 are set to make contact with arms 95, 96 as one or other of the pistons 23, 24 approaches its end of the cylinder. Contact with one or other of the arms 95, 96 causes it to turn the valve 32 to the position 40 shown in Fig. 4, wherein the passage leading from the cylinder end which is being vented is closed, and consequently the movement of the piston 22 (and the part operated thereby) checked or cushioned. The cams 90, 91 and the parts 45 associated therewith may be so contrived and set as to give considerable range and variety to the checking or cushioning action.

In the construction where the impeller housing 32 also serves as a valve, the friction of the liquid 50 driven by the impeller normally tends to rotate the housing and may even rotate the housing if left free to turn. In the arrangement shown in Figs. 1-6 the direction of rotation of the impeller 30 and direction in which the friction of 55 the liquid set in rotation thereby, acts is counter-clockwise, and as shown by the arrows, Figs. 2 and 5. Moreover, the force required to move the housing 32 in one direction will be greater than that required to move it in the opposite 60 direction. Suitable means may be provided to counteract the turning action on housing 32 of the fluid driven by the impeller. This means may for example be a spring 112 attached to 65 rocking beam 83 and acting thereon in a direction opposite to the pull of the housing 32 transmitted thereto through segment 69, shaft 70, arm 72 and link 77. The spring 112 will aid the solenoid 75^a in pulling to shift the valve (housing 32) and will counteract the pull of the friction 70 of the liquid on housing 32 when the solenoid 75^b pulls the valve (housing 32) to shift it in the opposite direction, thereby equalizing the force required to move the valve in either direction. 75 The force of the spring 112 may be adjusted by

suitable means 112^a, here shown as a bracket adjustably held on its support by binding screws.

It will be observed that spring 112 acts normally in a direction to aid the opening solenoid 75^a. This arrangement has a further advantage, both 5 in the construction where the friction of the liquid in the pump exerts a turning action on the valve, and where it does not. When neither solenoid 75^a or 75^b is energized, the tendency 10 of the spring 112 is to move the valve to the opening position, i. e. the position bringing about the opening of the door. In elevator practice it is of great importance to quickly reverse a closing movement of a door to avoid accidents, and the normal tendency of spring 112 is to move the valve 15 to door opening position and thus favor speed of operation in reversing the parts to door opening operation. When liquid flows under pressure through either the port 61 (or 61^a, 61^b) and passage 28 or port 60 (or 60^a, 60^b) and passage 20 27, the force of the stream will prevent movement of the valve under the action of either the spring 112 or the frictional drag on the valve (in that form where the valve is subject to such drag), but the tendency of spring 112 to move the valve 25 to door opening position persists, and furthermore in the present described arrangement, the spring will move the valve to door-opening position when the flow through the valve ceases and neither solenoid is energized. That is, after the 30 door is closed and the closing solenoid de-energized, the spring 112 will move the valve to door-opening position, so that even in case of failure of the solenoids, the valve will be in position for door-opening.

Means may be provided for opening or closing the door at different speeds. For example, it may be desired to open the door at a speed faster than the speed of closing. The means may be various; it is however very conveniently 40 combined with the valve 32 and its operating means. For example, abutments 85, 86 (Fig. 1) may be provided in the paths of cores 80, 81 of engine 75. By setting one of the abutments so that the core abutting the same cannot move 45 as far as the other core, one of the ports 60, 61 will not open one of channels 21, 28 as widely as the other. For example, if abutment 86 be set so as to allow core 81 less movement than core 80, the port 60 will only partially open, and the 50 closing movement of piston 22, and consequently the closing movement of the door D will be slower than the opening movement. Furthermore, by adjusting both abutments 85, 86 the speed of 55 opening and closing may be made faster or slower as the ports 60, 61 are more or less widely opened, as well as the differential movement heretofore described. Another very simple way of securing a difference in speed in opening and closing would be to vary the size of the ports 60 60, 61.

Operation

Assume the door shown in Fig. 1 to be in closed position, and it be desired to open it. The valve 65 32 will be in the position shown in Fig. 4. The electric motor 12 will ordinarily be previously started (running in one direction). A push button or other suitable device will then be operated to cause the electric engine 75 to shift the valve 70 75^a from the position shown in Fig. 4 to the position shown in Fig. 5. This will bring the impeller outlet 61 into registration with passage 28, and the compressed fluid from the impeller will push the piston 22 in a direction to move to the 75

- left, as viewed in Fig. 1. The piston will drive the thrust bar 50 so as to cause the rack 52 thereon to drive the gear segment 54 connected to the shaft 44 in a clockwise direction, thereby causing the arm *d* to swing upwardly and to the right, bringing the door with it to its open position. As the door approaches the end of its opening movement its action is preferably checked or cushioned through the means heretofore described, that is the cam 90 in this instance strikes the rock arm 96, and through the connections 94, 98, 101, 70, 69 and gear 67 moves the valve 32 to the position shown in Fig. 4, wherein both outlets 60, 61 from the impeller housing are cut off from the passages 27, 28. The movement of the door is thereby checked, and furthermore it is virtually locked in open position, inasmuch as the end 20 of the cylinder lately receiving compressed fluid is cut off from the supply of fluid driven by the impeller 30, through the closing action of the valve 32, and the end 19 of the cylinder lately venting fluid is also closed from further venting by the action of the valve 32 in cutting off the passage 27 from the reservoir 36, the valve being provided with solid portions 109 which cover and close the passages 27, 28 in the position of the valve shown in Fig. 4, so that flow to and from both ends of the cylinder 16 is cut off in the position of the valve shown in Fig. 4.
- After the door is open, the impeller may continue to turn in its housing without binding, as the liquid will "slip" or circulate and allow the motor to turn with about the same (or less) resistance as it does when driving the piston 22.
- The electric motor 12 is preferably a constant speed motor, so as to deliver a substantially constant torque, and not increase its torque or driving force when resistance is encountered to the movement of the piston 22, as would be the case if the door met an obstruction in either its opening or closing movement. This is a safety feature which prevents serious injury being done to anyone caught between the jamb and the door in closing.
- As the piston end 24 is being driven by fluid from the impeller, the opposite end 19 of the cylinder is being vented through the passage 27, the oil passing upwardly and downwardly in the passage 41 in the valve, and being drawn in through the impeller intake passages 38, 39, there being free access at the same time for the oil to rise in the reservoir 36, and thereby avoid the cylinder end 19 being vented against any pressure other than that necessary to overcome the resistance in the passages, which is slight.
- To close the door, the operation of the device is very similar to its operation in opening the door. The valve parts will be again in position shown in Fig. 4. The solenoid 15^b will be operated to rock the rocking beam 83 to move the connections to shift the valve so as to bring the impeller outlet passage 60 into registration with the passage 27 leading to the end 19 of the cylinder. The impeller will thereupon drive oil through the outlet passage 60, passage 27 and into cylinder 19 against the piston end 23. This will drive the piston to the right, producing a counter-clockwise rotation of gear segment 54 and shaft 44 carried thereby. Arm *d* connected to shaft 44 will move downwardly and to the left, sliding the door to closing position. As the door approaches closing position, the cam 91 will come into contact with rock arm 95, which rock arm will rotate the shaft 103 and through segment 104 rotate or shift the valve 32 again to the position shown in Fig. 4, wherein both passages 27 and 28 are cut off from the impeller. This completes a description of one cycle of operation of the device.

Referring to Figs. 7 and 8, illustrating another embodiment of the pump 14, the valve is formed separate from the impeller housing 32. The valve is designated by numeral 114 and is advantageously in the form of a sleeve between the impeller housing 32 and the motor casing. A spider-bracket 116 having a driving fit against the motor casing and set screws 118 bearing against neck 68 serve to prevent turning of the impeller housing 32. Ports 60^a and 61^a, 61^b are provided in valve 114. A gear 120 is provided on valve 114 and meshes with gear segments 69 and 104 on shafts 70 and 103 through which turning movements are imparted to valve 114. Blocks 122 of slightly greater width than the ports 60^a, 61^a, 61^b are placed in the middle of passages 27 and 28 dividing these passages into branches 27^a, 27^b and 28^a, 28^b.

In the position shown in Figs. 7 and 8 the valve 114 places impeller outlet 60 in communication with passage 27 through branch 27^b admitting fluid under pressure from the pump 14 through port 60^a to cylinder portion 19 (Fig. 1) thereby driving piston 22 to the right. Fluid from cylinder portion 20 is vented to reservoir 36 through passage 28, branch 28^b, port 61^b, and passage 41. At the end of the stroke of piston 22, cam 91 and arm 95 rocks shaft 93 causing worm gears 97, 100 to turn shaft 103 and segment 104 thereon so as to turn valve 114 through its gear 120 to a position where port 60^a is masked by block 122, and ports 61^a and 61^b are masked by the walls of the motor housing, thereby cutting off both passages 27, 28 from the pump 14 and reservoir 36. When the solenoid 15^b is energized to reverse the movement of piston 22, armature 81 pulls through link 77, arm 72, shaft 70 and segment 69 to turn valve 114 to bring port 61^a into register with discharge passage 61 and branch 28^a and passage 28, whereby fluid under pressure flows to cylinder portion 20, driving piston 22 to the left. At the same time port 60^a in valve 114 is brought into register with branch 27^a, passage 27 and passage 41, whereby fluid is vented from cylinder portion 19 to reservoir 36.

Referring to Figs. 9 and 10, the shaft 34 has fixed thereon two impellers 30, 30^a. The impeller housing 32 and valve 114 may be constructed as in Figs. 7 and 8, the impeller housing being stationary. The peripheral chamber 40 is connected by intake passages 38^a, 39^a leading to the intake on both sides of impeller 30^a. By the arrangement described fluid is acted on serially by the two impellers 30 and 30^a and its pressure increased. Discharge from impeller 30^a is into a peripheral chamber 40^a and from thence through outlet passages 60 and 61. Fluid vented from passages 27, 28 at proper times passes to reservoir 36 through passages 41. The operation of valve 114 is the same as described in reference to Figs. 7 and 8.

The checking, starting and stopping are accomplished resiliently and flexibly, shock being very greatly minimized, with consequent longer useful life of the mechanism and greater reliability. Furthermore, a very considerable effort is employed in modern practice for operating doors (the door operating engine having an applied force equal to about 200 pounds for example) in order to obtain the desired speed, and by the present means a push or effort of such

magnitude in a door operating engine may be obtained with a small electric motor turning at relatively high speed, as contrasted with a large electric motor, where electrical means are used for operating doors through mechanical connections. Furthermore, the electro-hydraulic motor can be reversed with greater facility and speed than electrical means such as referred to. This is a safety factor of major importance in elevator practice. The construction is furthermore greatly simplified, the functions of moving, checking, cushioning, stopping and locking the door being performed by one unit, whereas heretofore such simplicity could not be obtained in electrical operators, and could only be approached in pneumatic systems with their greater limitations as regards conveying compressed air to the moving car, expensive compressor equipment, and supervision required to keep in good working condition. Such parts as clutches and brakes are eliminated, for example. The limitation of the driving force by the use of a constant speed electric motor and the slip of the impeller in the liquid, when the door meets an obstruction is a further important safety feature of the invention.

The invention may receive other embodiments than those herein specifically illustrated and described.

30 What is claimed is:—

1. An electro-hydraulic motor, comprising a double-acting hydraulic motor, a pump comprising a rotary impeller for supplying liquid under pressure for driving said motor, an electric motor driving said impeller in one direction, and means for reversing the flow of liquid to said hydraulic motor while the electric motor is running, so that the direction of action of said hydraulic motor may be reversed and its reverse movement begun under the full driving force of the electric motor; said pump further comprising a rotatable housing having the function of a valve and forming a part of said means for reversing the flow of liquid to said hydraulic motor; said reversing means further comprising a motor-device and means for controlling said motor-device to effect reverse movements of said housing-valve; and means for counteracting the frictional drag on said housing of the liquid set in motion by said impeller, whereby the effort of said motor-device in reversing said housing valve is equalized.

2. An electro-hydraulic motor, comprising a double-acting hydraulic motor, a pump comprising a rotary impeller for supplying liquid under pressure for driving said motor, an electric motor driving said impeller in one direction, and means for reversing the flow of liquid to said hydraulic motor while the electric motor is running, so that the direction of action of said hydraulic motor may be reversed and its reverse movement begun under the full driving force of the electric motor, said reversing means including an impeller-housing provided with ports communicating with said double-acting hydraulic motor, and valve means thereon for controlling the said ports in said impeller housing.

3. An electro-hydraulic motor, comprising a double-acting hydraulic motor, a pump comprising a rotary impeller for supplying liquid under pressure for driving said motor, an electric motor driving said impeller in one direction, and means for reversing the flow of liquid to said hydraulic motor while the electric motor is running, so that

the direction of action of said hydraulic motor may be reversed and its reverse movement begun under the full driving force of the electric motor, and means for automatically cutting off the flow to said hydraulic motor at the end part of its movement to automatically stop the same; said cutting-off means comprising cams operated by said piston.

4. An electro-hydraulic motor, comprising a double-acting hydraulic motor, a double-acting reciprocating piston therein, a pump comprising a rotary impeller for supplying liquid under pressure for driving said double-acting piston, an electric-motor driving said impeller, a rock-shaft for applying the force developed upon said piston, driving connections to said rock shaft from a part of said double acting piston intermediate its ends, and means for automatically cutting off the flow to said hydraulic motor at the end part of its movement to stop the same, said latter means comprising cams on said rock-shaft.

5. An electro-hydraulic motor, comprising a double-acting hydraulic motor, a double-acting reciprocating piston therein, a pump comprising a rotary impeller for supplying liquid under pressure for driving said double-acting piston, an electric-motor driving said impeller, a rock-shaft for applying the force developed upon said piston, and driving connections from a part of said double-acting piston intermediate its ends to said rock shaft, means for reversing the flow of liquid to said hydraulic motor for driving the same in opposite directions, and means for automatically cutting off the flow to said hydraulic motor at the end part of its movement to stop the same.

6. An electro-hydraulic motor according to claim 5, wherein said cut-off means comprises cams on said rock-shaft, arms in the path of said cams and means connecting said arms and said reversing means for operating the latter.

7. An electro-hydraulic motor according to claim 5, wherein said cut-off means comprises cams on said rock-shaft, arms in the paths of said cams, and means connecting said arms and said valve for operating the latter, said last-named means comprising shafts passing through the motor housing above the liquid level.

8. An electro-hydraulic motor according to claim 5, said means for reversing the flow of said liquid comprising a motor-device, and a valve operated thereby, said motor permitting independent movement of said valve, said cut-off means comprising parts for moving said valve independently of said motor-device.

9. An electro-hydraulic motor, comprising a double-acting hydraulic motor, a pump comprising a rotary impeller for supplying liquid under pressure for driving said motor, an electric motor driving said impeller in one direction, and means for reversing the flow of liquid to said hydraulic motor while the electric motor is running, so that the direction of action of said hydraulic motor may be reversed and its reverse movement begun under the full driving force of the electric motor, said means for reversing the flow of said liquid comprising a motor-device and a valve operated thereby, said motor-device comprising a pair of solenoids, cores movable in said solenoids, and connections between said cores and said valve, and means for selectively energizing and de-energizing said solenoids, said cores and the valve being movable independently of said solenoids when the latter are de-energized.
